UNITED STATES PATENT OFFICE.

ANSEL HOWARD, JR., OF READSBORO, VERMONT.

MACHINE FOR MAKING WOODENWARE.

Specification of Letters Patent No. 27,803, dated April 10, 1860.

To all whom it may concern:

Be it known that I, ANSEL HOWARD, Jr., of Readsboro, in the county of Bennington and State of Vermont, have invented a new 5 and useful Machine for Manufacturing Wooden Dishes or Chopping-Trays; and I do hereby declare that the same is fully described and represented in the following specification and the accompanying drawings, of which—

Figure 1, is a top view. Fig. 2, a front elevation, and Fig. 3, a longitudinal section of such machine. Fig. 4, is a transverse section taken through the mechanism for 15 shaping the external surface of a tray.

In these drawings, A, denotes the main frame of the machine, there being within such frame another frame B, which is so supported between vertical guides as to be 20 capable of being moved either upward or downward, such frame B, being balanced by a weight, C, whose cords of suspension pass around pulleys arranged at the upper part of the frame A.

At the lower part of the frame A, are two 25 parallel and transverse ways or rails, D, D, which serve to support a carriage, E, to which a block of wood to be operated on is to be fastened by suitable appliances and to 30 be held by such while being reduced by the rotary cutters of the machine. Furthermore, the transverse movements of the said carriage, E, may be effected by means of a toothed rack *a*, applied to one side of it, and actuated by a pinion *b*, fixed on an upright shaft *c*, that by means of two gears, *e*, *f*, receives motion from a cranked shaft, *d*. On laying hold of the crank, *g*, of the shaft, *d*, and revolving it, the carriage, E, may be 35 put in movement either forward or backward, transversely underneath the cutters which are directly over it. These cutters are fixed in one rounded wheel or in two tapering cutter stocks, F, G which are fastened to 40 opposite ends of a pulley, H, and have the journals of their shaft supported by a frame I, that is suspended from a horizontal shaft, K. The said shaft, K, is supported by the frame, B, and so as not only to be capable of 45 being revolved freely thereon but of being moved or slid longitudinally from either one of two curved guides L, L, to the other as circumstances may require. Each of the 50 said guides is supported by a sliding or adjustable frame M, so applied to the frame, A, as to enable the guides L, L, to be ad-

justed with respect to their distance as under and also with respect to the carriage, E. The shaft, K, should not only be capable of rotating in the frame, L, but should have 55 collars, *i*, *i*, applied to it as shown in the drawings, the same being to cause the frame, I, to move endwise with the shaft while the latter is being moved longitudinally in order to carry the rotary cutters across a 60 block of wood in lateral directions of it.

The endwise movements of the shaft, K, are produced by means of a hand lever, N, suitably applied to the shaft and having its fulcrum at, O, as shown in the drawings. 70

A driving shaft, P, carrying a driving pulley, Q, and another pulley R, is placed at the upper part of the frame, A, and should receive motion from an endless belt carried about the pulley, Q. Another endless 75 belt should also be carried around the pulley, R, and a pulley, S, affixed on the shaft, K. Furthermore, a third endless belt should pass around the cutter stock pulley H, and a pulley, U, carried by the shaft, K. The 80 vertical motion of the frame, B, may be effected by turning a crank, *k*, carried by a shaft, *l*, (see Figs. 1, and 2). A pinion, *m*, on the said shaft, *l*, engages with a gear, *n*, affixed on a horizontal shaft, *o*, supported by 85 the frame, A. Two pinions, *p*, *p*, carried by the shaft *o*, engage with two racks, *q*, *q*, fastened to the frame, B, the whole serving to enable the vertical movements of the frame, A, to be controlled or effected by a 90 workman's hand applied to the crank *k*.

The above constitutes machinery for hollowing out a block of wood or forming the hollow or concave part of trays. The mechanism for rounding or shaping the outside 95 of it may be thus described. From the lower part of the frame A, two inclined posts, V, V, project as shown in the drawings, the upper part of each of such posts being curved and furnished on its inner surface with a crescent shaped groove *r*, see Fig. 4. Within such crescent shaped groove, *r*, there is a curved switch, *s*, having the form with respect to that of the said groove, as shown in Fig. 4. The grooves, *r*, are to 100 respectively receive two ears, *t*, *t*, of a plane or shave, W, connected with a vibratory lever, X, by two curved arms, *u*, *u*, whose lower ends are jointed to the front end of the said lever. The rear end of the lever is 105 jointed to a connecting rod, Y, whose upper end receives a crank pin, *v*, extended from

one side of the pulley R, the whole being so as to cause the plane or shave, W, during each revolution of the shaft, P, to have reciprocating movements in two curved paths, 5 one of which is under the switches while the other is over them. Each switch is a curved lever whose fulcrum pin y, extends through its post, V, and is attached to a helical spring, z, so applied to it and the post as to cause the lower arm of the switch 10 to be pressed toward the front side of its crescent shaped groove. These two switches are thus self-acting and should operate with their grooves in such manner as to cause the 15 ears of the plane stock while it is passing downward to move in front of the switches and while ascending to pass in rear of them, and so as to carry the plane away from the block of wood during each upward movement of the said plane and in contact with it 20 during each downward movement of the plane.

If we suppose the tray to be produced from the block is to have a flat bottom of an 25 elliptical or a rectangular shape and its sides and its ends to be rounded off from such bottom to the upper edge of the tray, the purpose of the plane is to produce this shaping of the sides and ends of the block. It 30 will accomplish this, provided the block after having been hollowed out by the rotary cutters is placed on a suitable bench or support and borne up against the plane and turned around as occasion may require for 35 the plane to reduce it to the necessary shape.

In the process of hollowing out the block while it is supported by the carriage, E, the frame, B, is first lowered so as to carry the rotary cutters into contact with the block, 40 the depression of the said frame being continued as circumstances may require, during the operation of hollowing the block. The

two guides L, L, having been properly adjusted, the shaft, K, during its descent is to have endwise movements from right to left, 45 and vice versa, and so as to carry it alternately in contact with the said guides, their curved form or inner surfaces serving to regulate the extent of each endwise movement of the shaft, so as to cause the cutters 50 as they descend into the block to cut the hollow with a curve transversely of it as well as to cut the block in longitudinal directions. During the said process of hollowing the block its carriage or holder, E, from time to 55 time is to be moved longitudinally in order to cause the block to be hollowed from end to end. Thus a movable carriage operated as described is necessary to the perfection of my machine, although it would be possible 60 to dispense with it and to support the block by other means so as to enable it to be moved longitudinally by the hand of the workman. By such mechanism, hollow elongated dishes or trays can be made with great facility 65 from blocks of wood.

In the above described machine I claim—

1. The arrangement and combination of the two curved guides, L, L, and a shaft, K, applied as described to a vertically moving 70 frame supporting cutters applied to it substantially as specified.

2. I also claim the mechanism for rounding the external surface of the block or tray, or preparing such with a flat bottom, and 75 round sides and ends, the said mechanism consisting of the plane, the curved guide grooves and switches arranged so as to operate substantially as specified.

ANSEL HOWARD, JR.
